COMPOUND YARN AND FABRIC

Charles E. McLean, Methuen, Mass., assignor to
 Patchogue-Plymouth Mills Corporation, Lawrence, Mass., a corporation of New York

Application March 22, 1933, Serial No. 662,101

2 Claims. (Cl. 139—420)

This invention relates to a type of woven material which is especially useful for rugs or other floor coverings and to the yarn of which the filling or that part of the filling which is on the top face is made.

In addition to giving body to the fabric and having good wearing qualities, this yarn and fabric have a feeling and appearance similar to what is known in the trade as drugged.

Moreover, it can be used on piazzas and other places exposed more or less to the weather as it is not materially affected by moisture.

I am aware that strips or tough paper have been twisted or revolved and formed into yarn and I am aware that such strips have been used as a core entirely covered with fiber as shown in the patents to Williams, No. 429,829, June 10, 1890 and No. 451,791, May 5, 1891 and Perkins, No. 446,926, February 24, 1891. Other combinations of strips of paper used in compound yarn and fabrics are shown in patents to Harrison, No. 961,441, June 14, 1910, Claviez, No. 999,008, July 25, 1911, Nanfeldt, No. 1,585,626, May 18, 1926 and No. 1,851,441, March 29, 1932. I am also aware that there are a great number of compound yarns made up of strands of various twisted materials.

The principal feature of this invention, however, is the use of a core made up of a plurality of strands, each of which is made of paper stock roving. Such roving is made without forming the paper stock into paper sheets and then cutting these into strips and twisting them. The paper stock strands or roving are the same or similar to those produced by the process shown in patent to Sherman, No. 1, 542,915, June 23, 1925.

Such paper stock may be produced from wood pulp or may be of any other paper stock, either pure or mixed with other short or even long fibres of cotton, ramie or hemp.

Wood fibre and hemp fibre treated and mixed make an excellent combination for producing the paper stock roving.

In the drawing, Fig. 1 is a greatly enlarged elevation of the core before being twisted with the covering strip, several of the strands which comprise it being shown as untwisted.

Fig. 2 is an elevation greatly enlarged of the covering strip before it is twisted together with the core.

Fig. 3 is an elevation greatly enlarged showing lengths of the core and covering strip side by side to show graphically that the covering strip is substantially longer than the core before twisting.

Fig. 4 is a diagrammatic elevation showing one

way of twisting the strip and core whereby the strip is wound spirally about the core.

Fig. 5 is a greatly enlarged cross section of a single ply fabric woven with my compound yarn as a filling.

Fig. 6 is a view similar to Fig. 5 of a fabric woven with filling threads made of my compound yarn at the top face and at the bottom face.

Fig. 7 is an elevation greatly enlarged showing how the covering strip spirals around the core after being twisted together.

Fig. 8 is a plan view of the double faced fabric shown in Fig. 6.

The preferred form of my compound yarn Y is made by taking three strands of paper stock roving 1, 2, 3 such as described, and giving them from two to three left turns to form a core yarn C. This core yarn C while under some tension is then twisted with a covering strip S which strip is originally longer than the core and is originally made up of one or more strands 11, 12, each strand preferably including seventy percent of wool or shoddy fiber and thirty percent of short rayon fiber.

The covering strip S has preferably been given five or six right turns before it is twisted with the core C and its length before twisting is substantially greater than the length of the core C. This greater length should be ten percent or more before twisting and the strip S, while being twisted with the core C, is subjected to little, if any, tension.

Preferably the strip S is unwound from a cheese or package such as indicated at P while the core C is pulled from a spool 20 at a sharp angle over and under rods 21, 21, 21, after which the two strands are brought together and carried through one of the arms 22 of a flyer F, being also wound thereby on a spool G.

Strip S, as shown, is unwound from the top of cheese P and thence runs over a guide rod 24.

The result of this construction is that the covering strip S forms a fairly close spiral around the core C and as the flyer F is revolving to the left, the core and cover are given three left turns with the result that in the compound yarn Y, the paper stock yarn core C has from five to six left turns while the strip S is untwisted so that it has from two to three left turns.

Obviously the terms in every case might be reversed and where the word right is used left might be substituted and where left is used right might be substituted.

This treatment causes strip S to become almost roving and with the lack of tension and the

untwisting, the spiralled covering strip S spreads out very loosely around the core C.

The original fiber yarn is substantially longer than the core yarn and the process of twisting them together, therefore, makes the difference in their length still greater.

Instead of wool and rayon in the proportion of seventy percent to thirty percent, the proportions may be nearly equal and there may be one 10 strand or several strands originally twisted together. The fiber may be of cotton, silk, ramie, jute, hemp or any other kind of fiber alone or mixed, according to the effect or the feeling which it is desired to give the surface of the rug or 15 other article manufactured from the compound yarn.

In every case I use a plurality of strands of 20 paper stock roving each substantially round and compact, hard twisted together for the core. Such a compound yarn with such a core used for a filling does not pull and tend to narrow the fabric as does one with a cotton core and needs no sizing and such a core is waterproof and clean while a twisted paper ribbon core picks up dirt and 25 breaks when wet. A core yarn of this kind particularly in an interwoven or multiple ply fabric does not pull and does tend to lie flat.

In making such a core yarn, another way is to 30 give a hard twist to the multiple strands of the core, say seven and a half to the inch and then to untwist these down to five by the same process in which the covering strip is untwisted down to two turns. A paper ribbon cannot be initially twisted enough to permit this.

The principal purpose of my compound yarn is 35 for use in making rugs or other similar floor coverings where a substantial body is desirable and where the feeling especially of the exposed surface of the rug is important.

Another important quality for rugs and floor 40 coverings, such as carpets, is, of course, strength to resist tearing and also the quality of resisting friction.

Preferably my compound yarn is used for the 45 filling of woven rugs. By filling, I mean what is known as the weft as distinguished from stuffing threads which are used in such articles and are usually parallel with the warp and are known as stuffing warps.

Preferably as shown in Fig. 6, I use weft or filling threads Y¹ and Y² of my yarn.

As shown, there are the top filling threads Y¹ and the bottom filling threads Y² and these are bound together by a suitable series of holding 55 warp threads W preferably of textile fiber such as cotton or wool.

In this preferred construction, I also show

stuffing warp threads H, H which may be made of the usual type of paper yarn which is formed by twisting strips of tough paper. This type of paper yarn has body and is, therefore, useful for filling, but is not as strong nor as solid as the 5 twisted paper stock roving such as Y, Y¹ or Y².

As shown, the holding warp threads bend above and below the filling threads and the process of weaving and their respective locations tend to pull the core C down toward the middle of the 10 rug leaving the spiral covering S on the outer surface at the top and also at the bottom.

I prefer to use relatively small strong and hard twisted holding warp threads relatively close together and these combined with the relatively 15 small hard twisted paper stock roving compound core yarn sink out of sight leaving the wool covering on the surface, but held tightly in place, the whole rug having body and the tendency to stay in place which cannot be obtained with a cotton 20 or a paper ribbon core.

As shown in Fig. 5, I may use my compound 25 yarn for the weft or filling in a single ply fabric. In this case, C represents the core and S the covering strip while M, M represent the warp 25 threads such as are used in any ordinary single ply weave.

I claim:

1. A woven fabric made up of stuffing warp threads made of paper, holding warp threads 30 made of twisted textile fibers; and a set of parallel top filling threads and a set of parallel bottom filling threads each of such filling threads being made up of a hard twisted core formed of a plurality of strands of paper stock roving twisted 35 together and a covering of relatively thick, loosely twisted short fibers spirally coiled around such core, the filling yarn threads being longer than the core threads and being sufficiently bent by the warp threads to force the spiral covering to the 40 top and bottom surfaces whereby relatively little of the core is exposed.

2. A woven fabric made up of stuffing warp threads made of paper, holding warp threads 45 made of twisted textile fibers; and filling threads 50 each of such filling threads being made up of a hard twisted core formed of a plurality of strands of paper stock roving twisted together and a covering of relatively thick, loosely twisted short fibers spirally coiled around such core, the filling 55 yarn threads being longer than the core threads and being sufficiently bent by the warp threads to force the spiral covering to the top and bottom surfaces whereby relatively little of the core is exposed.

CHARLES E. McLEAN.
